SWITCH CONTROL AND INDICATION SYSTEM

Charles W. Bell, Forest Hills, Pa., assignor to The Union Switch & Signal Company, Swissvale, Pa., a corporation of Pennsylvania

Application October 21, 1938, Serial No. 236,291

18 Claims. (Cl. 246—219)

My invention relates to a switch control and indication system, and particularly to improved means for insuring proper operation of the switch.

5 It has heretofore been proposed to provide a switch control system including a control lever for controlling the motor for operating a railway track switch, the control lever being movable between a normal and a reverse position and controlling operation of the switch motor to cause it to effect movement of the switch to the position corresponding to that occupied by the lever.

10 It has also been proposed to provide means associated with the control lever and known as the "quick switch" to control movement of the lever. The "quick switch" operates in such a manner that on movement of the control lever away from either of its positions to the other position, such as from the normal to the reverse position, the control lever must be moved substantially all of the way to the reverse position, and must remain in that position until the switch has moved to the reverse position and an indication is received of such movement of the switch before the control lever can be returned to the normal position. 15 This is advantageous as it prevents the switch and the switch control lever from getting out of correspondence with each other and as it prevents a false indication of the position occupied by the switch.

20 The "quick switch" mechanism is designed for and is adapted for use in mechanical interlocking machines, and is not adapted for use in all-relay type interlocking installations.

25 It is an object of my invention to provide a switch control and indication system which employs means which may be incorporated in an all-relay type of interlocking installation, and which will provide the operating results which 30 have heretofore been provided by the "quick switch" mechanism.

35 A further object of my invention is to provide an improved switch control and indication system in which a polarized auxiliary relay performs the functions which have been performed heretofore by the "quick switch" mechanism.

40 A further object of my invention is to provide an improved switch control system in which a polarized relay and the switch repeating relay 45 jointly control the normal and reverse switch indication or signal control relays in such a manner that on movement of the switch control lever to either of its positions, such as to the reverse position, the normal indication or signal control 50 relay cannot thereafter be energized unless the

switch completes its movement to the reverse position and effects energization of the reverse indication or signal control relay.

5 Another object of my invention is to provide an improved switch control system.

Other objects of my invention and features of novelty will be apparent from the following description taken in connection with the accompanying drawing.

10 I shall describe one form of apparatus embodying my invention, together with a modification which I may employ, and shall then point out the novel features thereof in claims.

15 In the drawing, Fig. 1 is a diagram of a system embodying my invention, and

Fig. 2 is a fragmentary diagrammatic view illustrating a modification which may be employed in the system shown in Fig. 1.

20 Referring to the drawing, the reference character W designates a railway track switch which is movable between a normal and a reverse position by suitable means such as an electric or a pneumatic motor, not shown. This motor is controlled by means well-known in the art, this means including a polarized switch control relay 25 WR.

25 The system includes, in addition, a polarized switch repeating relay WP, a normal indication relay NWP, a reverse indication relay RWP, and a polarized auxiliary control relay Z. The supply of current to the switch control relay WR is normally controlled by suitable pole changing means which may be part of an interlocking machine.

30 As here shown diagrammatically, the pole changing means comprises contacts 10 and 11 which are actuated by a control lever L and control the supply of current from a battery 14 to control wires 16 and 17. When the control lever L is in the normal position as shown, contact 10 35 connects wire 16 to terminal B of battery 14, while contact 11 connects wire 17 to terminal C of battery 14 so that current of one relative polarity, which may be considered normal polarity, is supplied to the wires 16 and 17.

40 Similarly, when the control lever L is in the reverse position, contact 10 connects wire 16 to terminal C of battery 14, while contact 11 connects wire 17 to terminal B of battery 14 so that current of reverse relative polarity is supplied 45 from battery 14 to wires 16 and 17.

45 The circuit from control wires 16 and 17 to the winding of the switch control relay WR is controlled by contacts 20 and 21 of lock relay LR. Contacts 20 and 21 are connected by wires 22 and 50 55

23 to the terminals of the winding of relay WR. Contact 20 when picked up engages a stationary contact to which is connected wire 16, while contact 21 when picked up engages a stationary contact to which is connected wire 17.

10 The circuit of the winding of the lock relay LR is controlled by means well-known in the art in accordance with traffic conditions in the vicinity of the switch W so that the winding of relay LR is energized only when it is safe to effect movement of the switch W between its two positions. At all other times the lock relay LR is deenergized and its contacts 20 and 21 are released.

15 The switch W has associated therewith means operative in accordance with the position occupied by the switch for controlling the polarity of the current supplied from a suitable source, such as a battery 25, to the winding of the switch 20 repeating relay WP. As shown, this means comprises contacts 27 and 28 which are connected by suitable wires to terminals of the winding of relay WP. When the switch W is in the normal position as shown in the drawing, contact 27 25 engages a stationary contact to which is connected wire 30 leading from terminal B of battery 25, while contact 28 engages a stationary contact to which is connected wire 31 leading from terminal C of battery 25 so that current of normal 30 relative polarity is supplied to the winding of relay WP.

Similarly, when the switch W is in the reverse position, contact 27 engages a stationary contact to which is connected a branch of wire 31 leading from terminal C of battery 25, while contact 35 28 engages a stationary contact to which is connected a branch of wire 30 leading from terminal B of battery 25 so that at this time the winding of relay WP is supplied with current of reverse 40 relative polarity.

The polarized auxiliary control relay Z is provided with two windings each of which has one terminal connected to a branch of wire 31 leading from terminal C of battery 25. The other 45 terminal of winding 32, which may be termed the first winding, is connected by a wire 33 to movable contact 34 of relay NWP, while contact 34 when picked up engages a stationary contact to which is connected a branch of wire 30 leading from terminal B of battery 25.

The other terminal of winding 36 of relay Z, which winding may be termed the second winding, is connected by wire 37 to contact 38 of relay RWP, while contact 38 when picked up engages a 55 stationary contact to which is connected a branch of wire 30 leading from terminal B of battery 25.

It will be seen that when the contacts of relay NWP are picked up, the first winding 32 of auxiliary relay Z is energized, while when the contacts of relay RWP are picked up, the second winding 36 of auxiliary relay Z is energized. The windings 32 and 36 of auxiliary relay Z are arranged so that when winding 32 is energized, the polar contact 40 is moved to its normal or 60 first position, and so that when winding 36 is energized, contact 40 is shifted to its reverse or second position. The internal construction of auxiliary relay Z is such that when both windings are deenergized, the contact 40 will remain 65 in its last operated position.

Contact 40 of relay Z has connected thereto a branch of wire 30 leading from terminal B of battery 25. Contact 40 when in the normal or first position, as shown in the drawing, engages 75 normal polar contact 41 which is connected by

a first supply wire 42 to movable contact 43 of relay RWP. Contact 43 when picked up engages a stationary contact to which is connected a branch of wire 30 leading from terminal B of battery 25.

5 Contact 40 of auxiliary relay Z when in the reverse or second position engages reverse polar contact 45 which is connected by a second supply wire 46 to contact 48 of relay NWP, while contact 48 when picked up engages a stationary contact to which is connected a branch of wire 30 leading from terminal B of battery 25.

The switch repeating relay WP has a movable contact 50 which when picked up engages a stationary contact 51 to which is connected a branch 10 of second supply wire 46. Contact 50 is connected by wire 52 to polar contact 54 of relay WP, while contact 54 when in its normal position, as shown, engages a stationary contact 55 which is connected by wire 56 to one terminal of the winding of relay NWP. The other terminal of the winding of relay NWP is connected by wire 58 to normal polar contact 59 of switch control relay WR. Contact 59 of relay WR is engaged at times by polar contact 60 which is connected by wire 61 25 to neutral contact 63 of relay WR. Contact 63 when picked up engages contact 64 to which is connected a branch of wire 31 leading from terminal C of battery 25.

The switch repeating relay WP has, in addition, 30 a neutral contact 66 which when picked up engages a stationary contact 68 to which is connected a branch of first supply wire 42, while the contact 66 is connected by wire 69 to polar contact 70. Contact 70 when in its reverse position 35 engages a stationary contact 71 which is connected by a wire 72 to one terminal of the winding of relay RWP. The other terminal of the winding of relay RWP is connected by wire 74 to reverse polar contact 75 of relay WR, while contact 75 is 40 engaged at times by polar contact 60 of relay WR.

Contact 20 of lock relay LR, when released, engages a stationary contact 78 which is connected by wire 79 to contact 80 of relay NWP. Contact 80, when picked up, engages a stationary 45 contact to which is connected a branch of wire 30 leading from terminal B of battery 25, while contact 80, when released, engages a stationary contact 81 which is connected by wire 83 to contact 84 of relay RWP. Contact 84, when picked 50 up, engages a stationary contact to which is connected a branch of wire 31 leading from terminal C of battery 25.

Contact 21 of relay LR, when released, engages a stationary contact 82 which is connected by 55 wire 85 to contact 86 of relay NWP. Contact 86, when picked up, engages a stationary contact to which is connected a branch of wire 31 leading from terminal C of battery 25, while contact 86, when released, engages a stationary contact 87 60 which is connected by wire 89 to movable contact 90 of relay RWP. Contact 90, when picked up, engages a stationary contact to which is connected a branch of wire 30 leading from terminal B of battery 25.

The switch control relay WR has a neutral contact 92 which is connected by wire 93 to a polar contact 95 of the relay WR. Contact 95, when in its normal position as shown, engages a normal stationary contact 96 to which is 70 connected a wire 97, while contact 95, when in its reverse position, engages a reverse stationary contact 98 to which is connected a wire 99. Neutral contact 92, when picked up, engages a stationary contact 100 to which is connected a wire 75

101. The wires 97, 99 and 101 lead to suitable means, not shown, for controlling the motor, not shown, for operating the switch W between its normal and reverse positions.

5 105. The relay NWP has a movable contact 105 to which is connected a wire 106, while the contact 105, when picked up, engages a stationary contact to which is connected a wire 107.

The relay RWP has a movable contact 110 to which is connected a wire 111, while the contact 110, when picked up, engages a stationary contact to which is connected a wire 112. The wires 106, 107, 111 and 112 are part of circuits for controlling the signals or other apparatus for governing the movement of trains over the track section in which the switch W is located.

The equipment is shown in the drawing in the position which it assumes when the switch W, the control lever L and the polar contacts of the switch control relay WR, the switch repeating relay WP, and of the auxiliary control relay Z are in their normal positions, and when the lock relay LR and the normal indication relay NWP are energized.

25 27. As the switch W is in its normal position, contact 27 engages the stationary contact to which is connected wire 30 leading from terminal B of battery 25, while contact 28 engages the stationary contact to which is connected wire 31 leading from terminal C of battery 25. Accordingly current of normal relative polarity is supplied to the winding of the switch repeating relay WP and the neutral contacts of this relay are picked up, while the polar contacts 54 and 70 are in their normal positions as shown.

30 35. As the winding of the relay WP is energized with current of normal relative polarity, the winding of the relay NWP is energized by current supplied from battery 25. The energizing circuit for the winding of relay NWP is traced from terminal B of battery 25 through wire 30, contact 48 of relay NWP, second supply wire 46, contacts 51-50 of relay WP, wire 52, normal polar contacts 54-55 of relay WP, wire 56, winding of relay NWP, wire 58, normal polar contacts 59-60 of relay WR, wire 61, contacts 63-64 of relay WR, and wire 31 to terminal C of battery 25.

40 45. At this time as the winding of relay NWP is energized, the contacts of this relay are picked up and contact 105 is closed, and the circuit of which wires 106 and 107 form a part is established to permit clearing of the signal or other apparatus controlled thereby.

50 55. As the polar contact 70 of relay WP is in the normal position, it does not engage contact 71 and the circuit of the winding of relay RWP, therefore, is interrupted and the contacts of relay RWP are released. Accordingly contact 110 60 interrupts the circuit of which the wires 111 and 112 form a part with the result that the signal or other apparatus controlled thereby cannot be conditioned to occupy the clear position.

65 60. As the winding of relay NWP is energized, contact 34 is picked up and completes the circuit for energizing the first winding 32 of auxiliary relay Z. The circuit for energizing this winding is traced from terminal B of battery 25 through wire 33, contact 34 of relay NWP, wire 33, winding 32 of relay Z and wire 31 to terminal C of battery 25. As the winding 32 of relay Z is energized, polar contact 40 is held in the normal or first position in engagement with contact 41.

70 75. As the lock relay LR is energized and as the control lever L is in the normal position, circuits

are established to supply current of normal relative polarity from battery 14 to the winding of the switch control relay WR with the result that the neutral contacts of this relay are picked up and the polar contacts of the relay are caused to 5 occupy their normal positions as shown.

If at this time the operator wishes to effect movement of the switch W from the normal to the reverse position, he may do so by moving the control lever L from its normal to its reverse position. On this movement of lever L, the contacts 10 and 11 are operated to effect the supply of current of reverse relative polarity from battery 14 to control wires 16 and 17 and thus to the winding of relay WR. When the polarity of the 15 current supplied to this winding is reversed, the neutral contacts 63 and 92 become released and thereafter again become picked up, while the polar contacts 60 and 95 are actuated from their normal to their reverse positions.

20 On release of the neutral contact 63 of relay WR and on movement of polar contact 60 away from the normal position out of engagement with contact 59, the previously traced circuit for energizing the winding of relay NWP is interrupted. 25 On deenergization of the winding of relay NWP, contact 34 becomes released, thereby interrupting the circuit for energizing the first winding 32 of relay Z. The internal construction of this relay Z is such, however, that on deenergization of 30 winding 32, contact 40 remains in the position in which it is found and continues to engage contact 41.

25 35. On movement of contact 95 of relay WR from the normal to the reverse position, the connection from wire 101 to wire 97 is interrupted and wire 101 is now connected to wire 98. On completion of the circuit between wires 101 and 99, the apparatus controlling the motor for operating the switch W is caused to effect operation of 40 the motor to produce movement of the switch W from the normal to the reverse position.

40 45. When the switch W moves away from the normal position, contacts 27 and 28 are moved out of engagement with the stationary contacts associated therewith, thereby interrupting the circuit for energizing the winding of relay WP. On deenergization of the winding of relay WP, the neutral contacts 50 and 66 of this relay become 50 released, thereby interrupting the circuits for 50 energizing the windings of relays NWP and RWP.

50 55. When the switch W attains the reverse position, contacts 27 and 28 are moved to their reverse positions so that contact 27 now engages a stationary contact to which is connected a branch of wire 31 leading from terminal C of battery 25, while contact 28 engages a stationary contact to which is connected a branch of wire 30 leading from terminal B of battery 25. Accordingly, current of reverse relative polarity is supplied to the winding of relay WP and the neutral contacts of this relay are picked up, while the polar contacts 54 and 70 are moved from their normal to their reverse positions.

60 65. On movement of polar contact 70 of switch repeating relay WP to its reverse position, it engages contact 71, thereby establishing a pick-up circuit for energizing the winding of relay RWP. This pick-up circuit is traced from terminal B 70 of battery 25 through wire 30, contacts 40-41 of auxiliary relay Z, first supply wire 42, contacts 68-66 of relay WP, wire 69, contacts 70-71 of relay WP, wire 12, winding of relay RWP, wire 14, reverse polar contacts 75-60 of relay WR, 75

wire 61, neutral contacts 63—64 of relay WR, and wire 31 to terminal C of battery 25.

On picking up of the contacts of relay RWP, a stick circuit is established to maintain the winding of relay RWP energized after movement of contact 40 of auxiliary relay Z from its normal or first position to its reverse or second position.

This stick circuit is traced from wire 39 through contact 43 of relay RWP to first supply wire 42 and thence to the winding of relay RWP over the previously traced circuit including the contacts of relay WP.

On picking up of the contacts of relay RWP, contact 38 becomes closed and establishes a circuit for energizing the second winding 36 of auxiliary relay Z. This circuit is traced from wire 30 leading from terminal B of battery 25 through contact 38 to wire 37 and thence through winding 36 to wire 31 leading from terminal C of battery 25. As winding 36 is energized, polar contact 40 of relay Z is shifted from its normal or first position to its reverse or second position.

On this movement of the contact 40 of relay Z, the pick-up circuit for relay RWP is interrupted, but the winding of relay RWP continues to be energized over the stick circuit established on picking up of its own contact 43.

On picking up of the contacts of relay RWP, contact 116 is closed and completes the circuit between wires 111 and 112 to thereby permit clearing of the signal or other control apparatus controlled by this circuit.

At this time as polar contact 54 of the switch repeating relay WP is in the reverse position, the circuit of the winding of relay NWP is interrupted and the contacts of this relay are released. Accordingly, contact 105 interrupts the connection between wires 106 and 107 with the result that the signal or other control apparatus controlled by this circuit cannot be cleared.

The equipment operates in a similar manner in effecting movement of the switch W from the reverse to the normal position. In order to effect movement of the switch W to the normal position, the control lever L is moved from its reverse to its normal position, thereby again effecting the supply of current of normal relative polarity to the control wires 16 and 17 and thus to the winding of relay WR.

On this reversal in the polarity of the current supplied to the winding of relay WR, the neutral contacts of this relay become released and thereafter again become picked up, while the polar contacts 60 and 95 of this relay are shifted from their reverse to their normal positions with the result that the control mechanism, not shown, for the motor, not shown, for the switch W is conditioned to effect operation of the motor to cause movement of the switch W from its reverse to its normal position.

On release of contact 63 of relay WR the circuit for energizing the winding of relay RWP is interrupted and the contacts of this relay become released. When contact 43 of relay RWP is released the stick circuit for energizing the relay winding is interrupted.

On movement of the switch W away from the reverse position, contacts 27 and 28 are moved out of engagement with the stationary contacts associated therewith, thereby interrupting the circuit for energizing the winding of relay WP. On deenergization of the winding of relay WP, neutral contacts 50 and 66 become released, and the circuit for energizing the winding of relay RWP is additionally interrupted by movement of

contact 66 out of engagement with contact 68, while contact 50 interrupts the circuit for energizing the winding of relay NWP.

On deenergization of the winding of relay RWP, its contacts become released and contact 116 5 interrupts the circuit between wires 111 and 112 to thereby prevent clearing of the signal or other mechanism controlled by this circuit.

In addition, on release of the contacts of relay RWP, contact 43 becomes released, thereby further interrupting the stick circuit for the winding of the relay RWP with the result that on subsequent picking up of the contacts of relay WP, the circuit for the winding of relay RWP is not completed. This will be true even though the neutral contact 66 of relay WP should close before polar contact 70 is moved out of engagement with contact 71, since at this time no connection is established from wire 30 leading from terminal B of battery 25 to first supply wire 42. This is true 20 since contact 43 of relay RWP is released, and since contact 40 of relay Z is in its reverse or second position. It will be seen, therefore, that on release of the contacts of relay RWP, this relay cannot thereafter again become energized 25 until the polar contacts of switch repeating relay WP are picked up in their reverse positions and contact 40 of auxiliary relay Z occupies its normal or first position as shown in the drawing.

On deenergization of the winding of relay RWP 30 contact 38 is released and interrupts the circuit of the second winding 36 of auxiliary relay Z. As previously explained, however, after deenergization of this winding contact 40 of the relay remains in the reverse or second position. 35

When the switch W reaches its normal position, contacts 27 and 28 again engage stationary contacts associated therewith to effect the supply of current of normal relative polarity to the winding of the switch repeating relay WP and 40 the neutral contacts of this relay become picked up, while the polar contacts of the relay are shifted from their reverse to their normal positions.

On picking up of neutral contact 50 of relay 45 WP and on movement of polar contact 54 to its normal position into engagement with contact 55, a circuit is established for energizing the winding of relay NWP. This circuit is traced from terminal B of battery 25 through wire 39, 50 reverse polar contacts 40—45 of relay Z, second supply wire 46, neutral contacts 51—50 of relay WP, wire 52, normal polar contacts 54—55 of relay WP and wire 56 to one terminal of the winding of relay NWP. The other terminal of 55 the winding of relay NWP is connected through wire 58, normal polar contacts 59—60 of relay WR, wire 61 and neutral contacts 63—64 of relay WR to wire 31 leading from terminal C of battery 25.

On picking up of the contacts of relay NWP, contact 48 engages a stationary contact to which is connected a branch of wire 39 to thereby establish a stick circuit for the winding of relay NWP which maintains the relay winding energized 60 after movement of contact 40 of auxiliary relay Z from its reverse to its normal position.

In addition, on picking up of the contacts of relay NWP, contact 34 completes the previously traced circuit for energizing the first winding 32 70 of relay Z, and on energization of winding 32 of relay Z, contact 40 of the relay is shifted from its reverse to its normal position. As just pointed out, however, on this movement of contact 40 the winding of relay NWP remains energized by 75

current supplied over the stick circuit established by its own contact 48.

On picking up of the contacts of relay NWP, contact 105 again completes the circuit between wires 106 and 107 to permit clearing of the signal or other apparatus controlled by this circuit.

The control system provided by this invention is arranged so that when the lock relay LR is deenergized, the connection from the control wires 16 and 17 to the winding of switch control relay WR is interrupted to thereby prevent a change in the polarity of the current supplied to this winding, while a circuit is established to maintain the winding of relay WR supplied with current of the same relative polarity as that with which it was supplied at the time the contacts of relay LR became released.

On deenergization of the winding of lock relay LR, contacts 20 and 21 become released, thereby interrupting connection from control wires 16 and 17 to wires 22 and 23 leading to the winding of switch control relay WR, while contact 20 engages contact 78 and contact 21 engages contact 82.

If at the time the contacts of the lock relay LR become released the winding of switch control relay WR is supplied with current or normal relative polarity, the polar contacts of the relay will be in their normal positions as shown in the drawing, at which time the switch W will also be in the normal position, while the normal indication relay NWP will be energized.

As the winding of relay NWP is energized, the contacts of this relay are picked up and contact 80 will engage the stationary contact to which is connected a branch of wire 30 leading from terminal B of battery 25, while contact 86 will engage a stationary contact to which is connected a branch of wire 31 leading from terminal C of battery 25. As a result, current of normal relative polarity is supplied from battery 25 to the winding of switch control relay WR over a circuit which includes wire 30 leading from terminal B of battery 25 through contact 80 of relay NWP, wire 79, contacts 78-20 of relay LR, wire 22, winding of switch control relay WR, wire 23, contacts 21-82 of relay LR, wire 85, contact 86 of relay NWP and wire 31 to terminal C of battery 25.

As the switch control relay WR continues to be supplied with current of normal relative polarity, the neutral contacts of this relay remain picked up, while the polar contacts of the relay are caused to remain in their normal positions, as shown, with the result that the apparatus for controlling the motor for operating the switch W continues to be conditioned to cause movement of the switch W to the normal position, or to cause it to remain in that position if it is already in such position.

In similar manner if when the contacts of the lock relay LR become released the winding of switch control relay WR is supplied with current of reverse relative polarity, circuits will be established to continue the supply of current of this relative polarity to the winding of relay WR.

When the winding of relay WR is supplied with current of reverse relative polarity, the polar contacts of this relay are in their reverse positions, and the switch W is also in its reverse position, while relay RWP is energized and relay NWP is deenergized.

Accordingly, on release of contacts 20 and 21 of lock relay LR, a circuit is established to supply current of reverse relative polarity from battery

25 to winding of relay WR, while the connection from control wires 16 and 17 to the relay winding is interrupted.

The circuit for energizing the winding of relay WR is traced from terminal B of battery 25 through wire 30, contact 90 of relay RWP, wire 89, contacts 87-86 of relay NWP, wire 85, contacts 82-21 of relay LR, wire 23, winding of relay WR, wire 22, contacts 20-78 of relay LR, wire 79, contacts 80-84 of relay NWP, wire 83, contact 84 of relay RWP and wire 31 to terminal C of battery 25.

As the winding of the switch control relay WR continues to be supplied with current of reverse relative polarity, the neutral contacts of this relay remain picked up, while the polar contacts of the relay are held in their reverse positions to condition the control apparatus for the switch motor to move the switch W to the reverse position or to maintain it in such position.

The control system provided by this invention is arranged so that on movement of the control lever L from one of its positions to the other to effect a change in the position occupied by the switch W, the switch must complete its movement and must effect energization of the indication relay for that position of the switch before the indication relay for the other position of the switch can subsequently be energized.

For purposes of illustration, it will be assumed that the switch W is in the normal position, and that an attempt is made to effect movement of the switch to the reverse position, but that the switch does not complete its movement to the reverse position.

In order to effect movement of the switch W from the normal to the reverse position, the control lever L is shifted from its normal to its reverse position, thereby effecting the supply of current of reverse polarity to the winding of relay WR. On this change in the polarity of the current supplied to the winding of relay WR, the neutral contacts of the relay become released and then subsequently become picked up, while the polar contacts of this relay are shifted from their normal to their reverse positions. On movement of contact 95 to the reverse position, the apparatus for controlling the motor for operating the switch W is conditioned to effect movement of the switch W from the normal to the reverse position.

As a result of the momentary release of contact 63 and the movement of contact 60 of relay WR from the normal to the reverse position, the circuit for energizing the winding of relay NWP is interrupted and the contacts of this relay thereupon become released with the result that contact 48 interrupts the stick circuit for the relay winding, while contact 105 interrupts the circuit between wires 106 and 107.

On movement of the switch W away from the normal position, contacts 27 and 28 are moved out of engagement with the stationary contacts associated therewith, thereby interrupting the supply of current of normal relative polarity to the winding of switch repeating relay WP with the result that the neutral contacts of this relay become released.

If movement of the switch W is obstructed, or if for any other reason the switch does not complete its movement to the reverse position, the polar contacts of relay WP will remain in their normal positions as shown and will maintain the circuit of the winding of relay RWP interrupted, while connection from terminal B of battery 25

to the winding of relay NWP remains interrupted since contact 40 of auxiliary relay Z is in the normal or first position as shown, while contact 48 of relay NWP is released.

If the control lever L is returned to the normal position before the switch W has completed its movement to the reverse position, current of normal relative polarity will be supplied to the winding of switch control relay WR and the polar contacts of this relay will be shifted from their reverse to their normal positions, while contact 95 will condition the control apparatus for the switch motor to effect operation of the motor to cause movement of the switch W from the reverse to the normal position.

On movement of the polar contact 60 of switch control relay WR to the normal position, a circuit is again established from wire 31 leading from terminal C of battery 25 to wire 58 leading to one terminal of the winding of the relay NWP.

When the switch W reaches the normal position, contacts 27 and 28 engage stationary contacts associated therewith to effect the supply of current of normal relative polarity to the winding of the switch repeating relay WP with the result that the neutral contacts 50 and 66 of this relay again become picked up, while the polar contacts 54 and 70 are held in their normal positions as shown. However, at this time no circuit is established between wire 30 leading from terminal B of battery 25 and the second supply wire 46 from which connection is established to one terminal of the winding of relay NWP. This is true since polar contact 40 of auxiliary relay Z remains in its normal or first position, while contact 48 of relay NWP is released.

Accordingly, relay NWP remains deenergized, while relay RWP is also deenergized since the circuit of the winding of this relay is interrupted by polar contact 60 of switch control relay WR as well as by polar contact 70 of relay WP. Both of the indication relays NWP and RWP are deenergized and the switch control circuits controlled by these relays are interrupted with the result that all of the signals associated with the track stretch in which the switch W is located occupy the stop position.

If the operator wishes to energize the normal indication relay NWP and thus permit clearing of the signals or other apparatus controlled by such relay, he may do so by first moving the control lever L to the reverse position and effecting movement of the switch W to the reverse position.

On movement of the control lever L to the reverse position, current of reverse relative polarity is supplied to the winding of relay WR and this relay operates to condition the apparatus for controlling the motor for the switch W to effect movement of the switch W from the normal to the reverse position.

On movement of the switch W away from the normal position, contacts 27 and 28 interrupt the circuit for supplying current of normal relative polarity to the winding of switch repeating relay WP and the neutral contacts of this relay thereupon become released. In order to effect movement of the switch W to the reverse position, it may be necessary to remove the obstruction which previously prevented movement of the switch W to the reverse position, if such obstruction exists. When the switch W reaches the reverse position, the contacts 27 and 28 establish circuits for supplying current of reverse relative polarity from the battery 25 to the winding of relay WP and the neutral contacts of this relay are again picked

up, while the polar contacts 54 and 70 are shifted from their normal to their reverse positions.

On this movement of contact 70, it engages contact 71, thereby completing the pick-up circuit for the winding of relay RWP, this circuit including wire 30 leading from terminal B of battery 25, normal polar contacts 40-41 of auxiliary relay Z, first supply wire 42, neutral contacts 68-66 of switch repeating relay WP, wire 69, reverse polar contacts 70-71, wire 72, winding of relay RWP, wire 74, reverse polar contacts 75-60 of relay WR, wire 61, neutral contacts 63-64 of relay WR and wire 31 to terminal C of battery 25.

On picking up of the contacts of relay RWP, its contact 43 establishes the stick circuit for the relay winding, while contact 38 establishes a circuit for energizing the second winding 36 of auxiliary relay Z. On energization of winding 36 of relay Z, contact 40 of the relay is shifted from the normal to the reverse position, but on movement of contact 40 out of engagement with contact 41, the circuit for energizing the winding of relay RWP is not interrupted since current is now supplied to this winding over the stick circuit established by contact 43.

After the switch W has completed its movement to the reverse position and relay RWP has been energized, the operator may return the switch to the normal position by returning the control lever L to the normal position, thereby effecting the supply of current of normal relative polarity to the winding of switch control relay WR. This relay thereupon operates as previously described to effect movement of the switch W to the normal position, while contacts 60 and 63 of relay WR operate to interrupt the circuit of the winding of the relay RWP.

When the switch W moves away from the reverse position, contacts 27 and 28 interrupt the circuit for energizing the winding of relay WP, and contact 66 of this relay additionally interrupts the circuit of the winding of the relay RWP. The contacts of relay RWP, therefore, become released and contact 43 interrupts the stick circuit for the relay winding so that on subsequent picking up of contact 66 of relay WP, the winding of relay RWP will not again be energized.

When the switch W attains the normal position, contacts 27 and 28 effect the supply of current of normal relative polarity to the winding of switch repeating relay WP, and since contact 40 of auxiliary relay Z is now in the reverse or second position, in which it engages contact 45 to which is connected the second supply wire 46, the contacts of relay WP establish the pick-up circuit for the winding of relay NWP as previously traced in detail. As the winding of relay NWP is energized its contact 48 establishes the stick circuit for the relay winding, while contact 105 completes the circuit between signal control wires 106 and 107.

The apparatus operates in a similar manner if, when the switch W is in the reverse position, the operator moves the control lever L away from its reverse position towards the normal position, and thereafter returns it to the reverse position before the switch W has completed its movement to the normal position.

When the switch W is in the reverse position, relays WR and WP are energized with current of reverse relative polarity, while relay RWP is energized and contact 40 of auxiliary relay Z is in the reverse or second position.

On movement of the control lever L away from

the reverse position, the circuit for energizing the winding of relay WR is interrupted and the neutral contacts of this relay thereupon become released. When contact 63 is released, the circuit for energizing the winding of relay RWP is interrupted and contact 43 of this relay is released to interrupt the stick circuit for maintaining the relay winding energized.

On movement of the switch W away from the reverse position, if such movement takes place, contacts 27 and 28 are operated to interrupt the supply of current of reverse relative polarity to the winding of switch repeating relay WP and the neutral contacts of this relay thereupon become released and additionally interrupt the circuit of the winding of relay RWP.

If the control lever L is now returned to the reverse position before the switch W reaches the normal position, current of reverse relative polarity will again be supplied to the winding of switch control relay WR and neutral contact 63 of this relay will again become picked up, while the polar contacts of the relay will remain in their reverse positions or will be returned to the reverse position if they have been moved therefrom, and will condition the motor control apparatus to effect operation of the motor to return the switch W to the reverse position if it is not already in that position.

On picking up of the contact 63 of relay WR, the circuit from wire 31 leading from terminal C of battery 25 is again completed to wire 74 leading to one terminal of the winding of relay RWP. However, at this time no connection is established from the other terminal of the winding of relay RWP to terminal B of battery 25 since contact 40 of auxiliary relay Z is in its reverse position, and therefore does not engage the contact 41, while contact 43 of relay RWP is released. Accordingly, the winding of relay RWP does not become energized on picking up of the contacts of relay WR or upon picking up of the neutral contacts of relay WP, which occurs when the switch W reaches the reverse position.

If the operator wishes to energize the reverse indication relay RWP and thus permit clearing of the signals or other apparatus controlled by such relay, he may do so by first moving the control lever L to the normal position, thereby conditioning the switch control relay WR to cause the switch motor to move the switch W to the normal position. As a result of this operation of switch control relay WR, contact 60 interrupts the circuit of the winding of relay RWP and again establishes a circuit from wire 31 to wire 58 leading to one terminal of the winding of relay NWP.

When the switch W reaches the normal position, contacts 27 and 28 again effect the supply of current of normal relative polarity to the winding of switch repeating relay WP, and the contacts of this relay become picked up to establish the pick-up circuit for the winding of relay NWP.

On picking up of the contacts of relay NWP, contact 34 completes the circuit for the first winding 32 of auxiliary relay Z, and on energization of winding 32, contact 40 is shifted from the reverse or second position to the normal or first position in which it engages contact 41 so that on subsequent energization of the winding of relay WP with current of reverse relative polarity, which occurs on movement of switch W to the reverse position, the pick-up circuit for the winding of relay RWP will be complete.

From the foregoing, it will be seen that the control system provided by this invention incorporates a polarized auxiliary relay Z which functions to provide the same operating results as has heretofore been provided by the "quick switch" mechanism.

In addition it will be seen that the system has the further advantage that it does not at any time prevent movement of the switch between its two positions. The effect of the system on movement of the switch control lever away from either of its positions and return to that position before the switch completes its movement is to cause both of the indication relays to be deenergized and thereby prevent clearing of the signals or other control apparatus controlled by these relays.

As the operator retains control of the switch and can effect movement thereof between its two positions he may repeatedly reverse the switch and thus break down an obstruction to movement of the switch, if such exists, and thus make it possible for the switch to complete its movement and effect energization of one of the indication relays and thereby restore the apparatus to its normal condition.

In applicant's system on movement of the switch control lever away from either of its positions, the circuit for energizing the indication relay for that position of the switch is interrupted and cannot thereafter be reestablished until the switch has been moved to its other position and the indication relay for such other position energized. When this has taken place, the switch W can be returned to its original position and on its return, the indication relay for that position will become energized.

Referring to Fig. 2 of the drawing, I have illustrated therein a modification which may be employed to provide additional insurance that the windings of the indication relays NWP and RWP can only be energized if the polar contacts of the switch repeating relay WP and of the auxiliary relay Z are in correspondence with each other and with the position occupied by the switch W.

The system shown in Fig. 2 is the same as that shown in Fig. 1 except as hereinafter pointed out in detail. In the system shown in Fig. 2, contact 40 of auxiliary relay Z, instead of being directly connected to terminal B of battery 25, is connected thereto by a circuit controlled by the relay WP and by the switch operated contacts.

Referring to the drawing, in the system shown in Fig. 2, contact 40 of auxiliary relay Z is connected by wire 120 to a neutral contact 121 of relay WP. Contact 121, when picked up, engages a stationary contact 122 which is connected by wire 124 to polar contact 125 of relay WP. Contact 125, when in the normal position as shown, engages a stationary contact 127 to which is connected a branch of the wire leading from switch operated contact 27. Contact 125, when in the reverse position, engages a stationary contact 128 to which is connected a branch of the wire leading from switch operated contact 28.

When the switch W is in the normal position, contacts 27 and 28 are in the positions shown, that is contact 27 engages a stationary contact to which is connected a branch of wire 30 leading from terminal B of battery 25, while contact 28 engages a stationary contact to which is connected a branch of wire 31 leading from terminal C of battery 25. With the contacts 27 and 28 in these positions current of normal relative

polarity is supplied to the winding of relay WP and the neutral contacts of this relay are picked up, while the polar contacts of the relay are held in their normal positions.

5. Accordingly, at this time contact 40 of auxiliary relay Z is connected to terminal B of battery 25 over a circuit which includes wire 120, contacts 121—122 of relay WP, wire 124, normal polar contacts 125—127 of relay WP, switch operated contact 27 and wire 30.

As explained in detail in connection with the system shown in Fig. 1, at the time the switch W is moved to the normal position contact 40 of relay Z is in the reverse position in which it engages contact 45 to which is connected the second supply wire 46. Accordingly, on movement of the switch W to the normal position with resultant operation of the contacts 27 and 28 to effect the supply of current of normal relative polarity to winding of relay WP, the contact 40 of auxiliary relay Z establishes connection from terminal B of battery 25 to the second supply wire 46 so that the winding of relay NWP may become energized.

25. Similarly, on movement of the switch W to the reverse position the contacts 27 and 28 are shifted so that contact 27 now engages a stationary contact to which is connected a branch of wire 31 leading from terminal C of battery 25, while contact 28 now engages a stationary contact to which is connected a branch of wire 30 leading from terminal B of battery 25. Current of reverse relative polarity is, therefore, supplied to the winding of relay WP and the neutral contacts of this 35 relay will be picked up, while the polar contacts of the relay will be moved to their reverse positions. On movement of contact 125 to the reverse position it engages reverse polar contact 128 which at this time is connected by switch operated contact 28 to terminal B of battery 25. Connection is established, therefore, from terminal B of battery 25 to contact 40 of auxiliary relay Z, the circuit being traced from wire 30 leading from terminal B of battery 25 through 45 switch operated contact 28, reverse polar contacts 128—125 of relay WP, wire 124, contacts 122—121 of relay WP, and wire 120 to contact 40.

When the switch W is in the normal position, contact 40 of auxiliary relay Z is caused to occupy the normal position as shown, as explained in detail in connection with the system shown in Fig. 1. Accordingly, when the switch W is moved to the reverse position and the winding of relay WP is supplied with current of reverse relative 50 polarity and its polar contacts shift to their reverse position, contact 40 establishes connection from terminal B of battery 25 to the first supply wire 42 from which connection is established to energize the winding of relay RWP.

60. The modification shown in Fig. 2 operates so that if for any reason on movement of the switch W from one of its positions to the other, the polar contacts of relay WP fail to move to the corresponding position, contact 40 of auxiliary relay Z will not be connected to terminal B of battery 25, but will be connected to terminal C of the battery, if the contact is not completely disconnected therefrom.

If, for example, the switch W is being moved 70 from the normal position to the reverse position and the polar contacts of relay WP remain in their normal positions after switch W attains the reverse position, contact 125 will engage contact 127 which is connected to switch operated contact 27. In the reverse position of the switch

W contact 27 engages a stationary contact to which is connected a branch of wire 31 leading from terminal C of battery 25. Accordingly, if the circuit leading to contact 40 of relay Z is not interrupted by contact 121 of relay WP, contact 40 will be connected to terminal C of battery 25, and not to terminal B. Contact 40 is connected to terminal B only if the polar contacts of relay WP are in correspondence with the switch operated contacts 27 and 28.

10. Similarly, if the switch W is moved from the reverse to the normal position and the polar contacts of relay WP fail to move to their normal positions, but remain in their reverse positions, connection will not be established between contact 40 of relay Z and terminal B of battery 25, and contact 40, if connected to either terminal of battery 25, will be connected to terminal C of the battery. When the polar contact 125 of relay WP is in the reverse position it engages contact 128 which is connected to switch operated contact 28, while contact 28, in the normal position of the switch W, engages a stationary contact to which is connected a branch of wire 31 leading from terminal C of battery 25.

20. From the foregoing it is clear that in the modification shown in Fig. 2 contact 40 of auxiliary relay Z is not connected to terminal B of battery 25 unless there is correspondence between the positions of the switch operated contacts and the polar contacts of relay WP. Accordingly, at times when the polar contacts of relay WP are out of correspondence with the switch operated contacts 27 and 28, connection cannot be established by contact 40 of auxiliary relay Z from terminal B of battery 25 to either the first supply wire 42 or the second supply wire 46, and hence the pick-up circuits for the indication relays NWP and RWP cannot be established. Both of these relays, therefore, will remain deenergized and 30 there is no possibility that a false clear indication will be given.

35. The system shown in Fig. 1 normally operates to prevent energization of either indication relay unless the relay WP operates in the intended manner. Thus it will be seen that when the switch W is in the normal position, relay NWP is energized and its contact 34 establishes the circuit for the first winding 32 of relay Z, while winding 32, when energized, effects movement of 45 contact 40 to the normal or first position in which it engages contact 41 to which is connected the first supply wire 42.

40. If the switch W is now moved away from the normal position, the circuit of the winding of relay NWP is interrupted by the contacts of relay WR, while on release of the contacts of relay NWP its own contact 48 interrupts the stick circuit for energizing its own winding. When the switch W reaches the reverse position, the polar contacts of relay WP normally shift to their reverse positions, but even if they should remain in the normal position and the neutral contacts of the relay should remain picked up, a circuit would not be established to energize either of the 50 indication relays. This would be true since contact 70 of relay WP, when in the normal position, does not engage contact 71, and hence does not establish the pick-up circuit for relay RWP, and while contact 54 of relay WP, when in the 55 normal position, engages contact 55, the pick-up circuit for relay NWP is not complete since contact 40 of relay Z is out of engagement with contact 45.

60. The system operates in a similar manner if on 70

movement of the switch W from the reverse to the normal position the polar contacts of relay WP fail to shift to the normal position and remain in the reverse position instead. Under these circumstances neither indication relay is energized.

In the system shown in Fig. 1 of the drawing, however, if there should be a simultaneous failure of the relays WP and Z to operate as intended, there is a possibility that one of the indication relays might be energized at a time when it should not be.

For example, when the switch W is in the normal position, the relay NWP is energized and its contact 34 establishes the circuit for the first winding 32 of auxiliary relay Z. Winding 32 should now be energized and contact 40 should move from the reverse or second position to the normal or first position. For purposes of illustration it is assumed that relay Z does not operate as intended and that contact 40 of the relay remains in the reverse position in engagement with contact 45.

If the switch W is now moved to the reverse position, the circuit of the winding of relay NWP will be interrupted by the contacts of relay WR. When the switch reaches the reverse position, the polar contacts of relay WP should move from the normal to the reverse position. For purposes of illustration, it is assumed, however, that the relay WP fails to operate as intended, and that the polar contacts of the relay WP remain in their normal positions and that the neutral contacts of the relay remain picked up. As a result of this simultaneous failure of the relays WP and Z to operate in the intended manner, a circuit is established from wire 30 leading from terminal B of battery 25 to one terminal of the winding of relay NWP.

As long as the relay WR continues to be supplied with current of reverse relative polarity and its polar contacts remain in their reverse positions, no connection is established from the other terminal of the winding of relay NWP to terminal C of battery 25, and the winding, therefore, remains deenergized.

However, on subsequent supply of current of normal relative polarity to the relay WR, and resultant movement of the polar contacts of this relay to their normal positions to effect corresponding movement of the switch W, the circuit from terminal C of battery 25 to wire 58 leading to a terminal of the winding of relay NWP is complete. As connection is established between the other terminal of the winding of relay NWP and terminal B of battery 25 at this time due to faulty operation of relays WP and Z, as explained above, the winding of relay NWP will be energized immediately upon movement of the polar contacts of relay WR to their normal positions. The relay NWP, therefore, would be energized and would permit clearing of the signals controlled thereby even though the switch W has not reached the normal position, and, if movement of the switch were obstructed, might not move to that position.

A similar situation would result if the auxiliary relay Z should fail at a time when its polar contact 40 is in its normal or first position, in which it engages contact 41, and if there should be a simultaneous failure of the relay WP so that its polar contacts stick in their reverse positions. Under these circumstances, on movement of the polar contacts of relay WR to their reverse positions the winding of relay RWP will be energized

even though the switch W is not in the reverse position and may not reach that position.

The modification shown in Fig. 2 of the drawing is arranged to prevent energization of the relays NWP and RWP in the event of simultaneous failure of the relays WP and Z.

As previously explained in detail, in the system shown in Fig. 2, contact 40 of relay Z is connected to terminal B of battery 25 only when the positions of the polar contacts of relay WP correspond to the position of the switch W. When the switch W and the contacts of relay WP are out of correspondence, contact 40 of auxiliary relay Z is connected to terminal C of battery 25, if any circuit is established to this contact.

Accordingly, if because of faulty operation of relays WP and Z, connection is established to one terminal of the winding of relay NWP or RWP at a time when this connection should not be made, no objectionable results will follow. Under such circumstances, on operation of relay WR to complete the circuit leading from the other terminal of the winding of either of the indication relays, both terminals of the relay winding will be connected to terminal C of battery 25, and the winding, therefore, will not be energized, while the signal or other apparatus controlled by the relay cannot assume the clear condition.

From the foregoing it will be seen that the modification shown in Fig. 2 of the drawing provides means to prevent undesired energization of the indication relays in the event of simultaneous failure of the relays WP and Z.

Although I have herein shown and described one form of apparatus embodying my invention, together with a modification which I may employ, it is understood that various changes and modifications may be made therein within the scope of the appended claims without departing from the spirit and scope of my invention.

Having thus described my invention, what I claim is:

1. In combination, a railway track switch movable between a normal and a reverse position, means for effecting movement of said switch between its two positions, a normal indication device and a reverse indication device, a source of current, an auxiliary device controlled by said indication relays, said auxiliary device having an element movable between a first position in which it establishes connection from said source of current to a first supply circuit and a second position in which it establishes connection from said source of current to a second supply circuit, the normal indication device being operative when energized to effect movement of said auxiliary device element to its first position, the reverse indication device being operative when energized to effect movement of the auxiliary device element to its second position, a member movable in accordance with movement of the switch, said member being operative when and only when the switch is in the normal position to effect connection from the second supply circuit to the winding of the normal indication device and being operative when and only when the switch is in the reverse position to effect connection from the first supply circuit to the winding of the reverse indication device, said indication devices controlling means for governing movement of trains across said switch.

2. In combination, a railway track switch movable between a normal and a reverse position, a motor for moving said switch between its two positions, a control device having a normal condi-

tion in which it effects operation of the motor to move the switch to the normal position and also having a reverse condition in which it effects operation of the motor to move the switch to the reverse position, means for selectively causing said control device to assume one or the other of its conditions, a normal indication relay and a reverse indication relay, a source of current, an auxiliary device controlled by said indication relays, said auxiliary device having an element movable between a first position in which it establishes connection from said source of current to a first supply circuit and a second position in which it establishes connection from said source of current to a second supply circuit, the normal indication relay being operative when energized to effect movement of said auxiliary device element to its first position, the reverse indication relay being operative when energized to effect movement of the auxiliary device element to its second position, a member movable in accordance with movement of the switch, said member being operative when and only when the switch is in the normal position to effect connection from the second supply circuit to the winding of the normal indication relay and being operative when and only when the switch is in the reverse position to effect connection from the first supply circuit to the winding of the reverse indication relay, said control device also controlling the circuits of the indication relays, said control device being operative when and only when in its normal condition to establish the circuit of the normal indication relay and being operative when and only when in its reverse condition to establish the circuit of the reverse indication relay.

3. In combination, a railway track switch movable between a normal and a reverse position, means for effecting movement of said switch between its two positions, a normal indication relay and a reverse indication relay, a source of current, an auxiliary device controlled by said indication relays, said auxiliary device having an element movable between a first position in which it establishes connection from said source of current to a first supply circuit and a second position in which it establishes connection from said source of current to a second supply circuit, the normal indication relay being operative when energized to effect movement of said auxiliary device element to its first position, the reverse indication relay being operative when energized to effect movement of the auxiliary device element to its second position, the auxiliary device element being adapted on movement to either of its positions to remain in such position until caused to move therefrom by one of said indication relays, a member movable in accordance with movement of the switch, said member being operative when and only when the switch is in the normal position to effect connection from the second supply circuit to the winding of the normal indication relay and being operative when and only when the switch is in the reverse position to effect connection from the first supply circuit to the winding of the reverse indication relay.

4. In combination, a railway track switch movable between a normal and a reverse position, means for effecting movement of said switch between its two positions, a normal indication relay and a reverse indication relay, a source of current, an auxiliary device controlled by said indication relays, said auxiliary device having an element movable between a first position in

which it establishes connection from said source of current to a first supply circuit and a second position in which it establishes connection from said source of current to a second supply circuit, the normal indication relay being operative when energized to effect movement of said auxiliary device element to its first position, the reverse indication relay being operative when energized to effect movement of the auxiliary device element to its second position, a member movable in accordance with movement of the switch, said member being operative when and only when the switch is in the normal position to effect connection from the second supply circuit to the winding of the normal indication relay and being operative when and only when the switch is in the reverse position to effect connection from the first supply circuit to the winding of the reverse indication relay, and circuits controlled by said indication relays and adapted to control means for governing movement of trains across said switch.

5. In combination, a railway track switch movable between a normal and a reverse position, means for effecting movement of said switch between its two positions, a source of current, an auxiliary relay having a first and a second winding and having an element movable between a first and a second position by said windings, said element being movable to its first position when the first winding is energized and being operative in said first position to effect connection from said source of current to a first supply circuit, said element being movable to its second position when the second winding is energized and being operative in said second position to effect connection from said source of current to a second supply circuit, a normal and a reverse indication relay, the normal indication relay being operative when energized to effect connection from said source of current to said second supply circuit and to effect the supply of current to the first winding of said auxiliary relay, the reverse indication relay being operative when energized to effect connection from said source of current to said first supply circuit and to effect the supply of current to the second winding of said auxiliary relay, a member movable in accordance with movement of the switch, said member being operative when and only when the switch is in the normal position to effect connection from the second supply circuit to the winding of the normal indication relay and being operative when and only when the switch is in the reverse position to effect connection from the first supply circuit to the winding of the reverse indication relay, and circuits controlled by said indication relays and adapted to control means for governing movement of traffic across said switch.

6. In combination, a railway track switch movable between a normal and a reverse position, a motor for moving said switch between its two positions, a control device having a normal condition in which it effects operation of the motor to move the switch to the normal position and having a reverse condition in which it effects operation of the motor to move the switch to the reverse position, means for selectively causing said control device to assume one or the other of its conditions, a source of current, an auxiliary relay having a first and a second winding and having an element movable between a first and a second position by said windings, said element being movable to its first position when the first

winding is energized and being operative in said first position to effect connection from said source of current to a first supply circuit, said element being movable to its second position when the second winding is energized and being operative in said second position to effect connection from said source of current to a second circuit, a normal and a reverse indication relay, the normal indication relay being operative when energized to effect connection from said source of current to said second supply circuit and to effect the supply of current to the first winding of said auxiliary relay, the reverse indication relay being operative when energized to effect connection from said source of current to said first supply circuit and to effect the supply of current to the second winding of said auxiliary relay, a member movable in accordance with movement of the switch, said member being operative when and only when the switch is in the normal position to effect connection from the second supply circuit to the winding of the normal indication relay and being operative when and only when the switch is in the reverse position to effect connection from the first supply circuit to the winding of the reverse indication relay, said control device also controlling the circuits of the windings of said indication relays, said control device being operative when and only when in its normal condition to establish the circuit of the normal indication relay and being operative when and only when in its reverse condition to establish the circuit of the reverse indication relay.

7. In combination, a railway track switch movable between a normal and a reverse position, means for moving said switch between its two positions, an auxiliary relay having a first and a second winding and having an element movable between a first and a second position by said windings, said element being moved to the first position on energization of the first winding and being moved to the second position on energization of the second winding, a normal and a reverse indication relay, a movable member movable between a normal and a reverse position in accordance with movement of the switch, means operable when the auxiliary relay element is in its first position and the movable member is in the reverse position to energize the reverse indication relay, means operable when the auxiliary relay element is in its second position and the movable member is in its normal position to energize the normal indication relay, the normal indication relay being operative when energized and the movable member is in its normal position to establish a stick circuit for energizing its own winding, the reverse indication relay being operative when energized and the movable member is in its reverse position to establish a stick circuit for energizing its own winding, the normal indication relay being operative when energized to cause the auxiliary device to assume its first condition, and the reverse indication relay being operative when energized to cause the auxiliary device to assume its second condition.

8. In combination, a railway track switch movable between a normal and a reverse position, means for moving said switch between its two positions, an auxiliary relay having a first and a second winding and having an element movable between a first and a second position by said windings, said element being moved to the first position on energization of the first winding and being moved to the second position on energiza-

tion of the second winding, a normal and a reverse indication relay, a movable member movable between a normal and a reverse position in accordance with movement of the switch, means operable when the auxiliary relay element is in its first position and the movable member is in the reverse position to energize the reverse indication relay, means operable when the auxiliary relay element is in its second position and the movable member is in its normal position to energize the normal indication relay, the normal indication relay being operative when energized and the movable member is in its normal position to establish a stick circuit for energizing its own winding, the reverse indication relay being operative when energized and the movable member is in its reverse position to establish a stick circuit for energizing its own winding, the normal indication relay being operative when energized to establish a circuit for energizing the first winding of the auxiliary relay and the reverse indication relay being operative when energized to establish a circuit for energizing the second winding of the auxiliary relay, and circuits controlled by said normal and reverse indication relays and adapted to control means for governing movement of trains over the track switch.

9. In combination, a railway track switch movable between a normal and a reverse position, means for moving said switch between its two positions, an auxiliary device having a first condition and a second condition, a normal and a reverse indication relay, a movable member movable between a normal and a reverse position in accordance with movement of the switch, means operable when the auxiliary device is in its first condition and the movable member is in the reverse position to energize the reverse indication relay, means operable when the auxiliary device is in its second condition and the movable member is in the normal position to energize the normal indication relay, the normal indication relay being operative when energized and the movable member is in the normal position to establish a stick circuit for energizing its own winding, the reverse indication relay being operative when energized and the movable member is in the reverse position to establish a stick circuit for energizing its own winding, the normal indication relay being operative when energized to cause the auxiliary device to assume its first condition, and the reverse indication relay being operative when energized to cause the auxiliary device to assume its second condition.

10. In combination, a railway track switch movable between a normal and a reverse position, means for moving said switch between its two positions, an auxiliary device having a first condition and a second condition, a normal and a reverse indication relay, a movable member movable between a normal and a reverse position in accordance with movement of the switch, means operable when the auxiliary device is in its first condition and the movable member is in the reverse position to energize the reverse indication relay, means operable when the auxiliary device is in its second condition and the movable member is in the normal position to energize the normal indication relay, the normal indication relay being operative when energized and the movable member is in the normal position to establish a stick circuit for energizing its own winding, the reverse indication relay being operative when energized and the movable member is in the reverse position to establish a

- stick circuit for energizing its own winding, the normal indication relay being operative when energized to cause the auxiliary device to assume its first condition and the reverse indication relay being operative when energized to cause the auxiliary device to assume its second condition, and circuits controlled by said normal and reverse indication relays and adapted to control means for governing movement of trains over the track switch.
11. In combination, a railway track switch movable between a normal and a reverse position, an auxiliary device having a first condition and a second condition, a normal and a reverse indication relay, a member movable between a normal and a reverse position in accordance with movement of the switch, means operable when the auxiliary device is in its first condition and the movable member is in the reverse position to energize the reverse indication relay, means operable when the auxiliary device is in its second condition and the movable member is in the normal position to energize the normal indication relay, the normal indication relay being operative when energized and the movable member is in the normal position to establish a stick circuit for energizing its own winding, the reverse indication relay being operative when energized and the movable member is in the reverse position to establish a stick circuit for energizing its own winding, the normal indication relay being operative when energized to cause the auxiliary device to assume its first condition, and the reverse indication relay being operative when energized to cause the auxiliary device to assume the second condition, a control mechanism having a normal position in which it effects movement of the switch to the normal position and having a reverse position in which it effects movement of the switch to the reverse position, the control mechanism also controlling the circuits of the windings of the normal and reverse indication relays, said control mechanism being operative when and only when in its normal condition to establish the circuit of the normal indication relay and being operative when and only when in its reverse condition to establish the circuit of the reverse indication relay.
12. In combination, a railway track switch movable between a normal and a reverse position, an auxiliary device having a first condition and a second condition, a normal and a reverse indication relay, a member movable between a normal and a reverse position in accordance with movement of the switch, means operable when the auxiliary device is in its first condition and the movable member is in the reverse position to energize the reverse indication relay, means operable when the auxiliary device is in its second condition and the movable member is in the normal position to energize the normal indication relay, the normal indication relay being operative when energized and the movable member is in the normal position to establish a stick circuit for energizing its own winding, the reverse indication relay being operative when energized and the movable member is in the reverse position to establish a stick circuit for energizing its own winding, the normal indication relay being operative when energized to cause the auxiliary device to assume its first condition and the reverse indication relay being operative when energized to cause the auxiliary device to assume the second condition, a polarized relay operative when energized with current of normal relative polarity

to effect movement of the switch to the normal position and being operative when energized with current of reverse relative polarity to effect movement of the switch to the reverse position, said polarized relay also controlling the circuits of the normal and reverse indication relays, said polarized relay being operative when and only when energized with current of normal relative polarity to establish the circuit of the normal indication relay and being operative when and only when energized with current of reverse relative polarity to establish the circuit of the reverse indication relay, and means for selectively supplying current of one polarity or the other to said polarized relay.

13. In combination, a railway track switch movable between a normal and a reverse position, means for moving said switch between said positions, an auxiliary device having a first condition and a second condition, a polarized relay, means operative when and only when the switch is in the normal position for supplying current of normal relative polarity to said polarized relay, means operative when and only when the switch is in the reverse position for supplying current of reverse relative polarity to said polarized relay, a normal and a reverse indication relay, means operable when the auxiliary device is in its first condition and the polarized relay is supplied with current of reverse polarity to establish a circuit for energizing the reverse indication relay, means operable when the auxiliary device is in its second condition and the polarized relay is supplied with current of normal polarity for energizing the normal indication relay, the reverse indication relay being operative when energized and the polarized relay is supplied with current of reverse relative polarity to establish a stick circuit for energizing its own winding, the normal indication relay being operative when energized and the polarized relay is supplied with current of normal relative polarity to establish a stick circuit for energizing its own winding, the normal indication relay being operative when energized to cause the auxiliary device to assume its first condition, the reverse indication relay being operative when energized to cause the auxiliary device to assume its second condition.

14. In combination, a railway track switch movable between a normal and a reverse position, means for moving said switch between said positions, an auxiliary device having a first condition and a second condition, a polarized relay, means operative when and only when the switch is in the normal position for supplying current of normal relative polarity to said polarized relay, means operative when and only when the switch is in the reverse position for supplying current of reverse relative polarity to said polarized relay, a normal and a reverse indication relay, means operable when the auxiliary device is in its first condition and the polarized relay is supplied with current of reverse polarity to establish a circuit for energizing the reverse indication relay, means operable when the auxiliary device is in its second condition and the polarized relay is supplied with current of normal polarity for energizing the normal indication relay, the reverse indication relay being operative when energized and the polarized relay is supplied with current of reverse relative polarity to establish a stick circuit for energizing its own winding, the normal indication relay being operative when energized and the polarized relay is supplied with current of normal relative polarity to establish a stick circuit

- for energizing its own winding, the normal indication relay being operative when energized to cause the auxiliary device to assume its first condition, the reverse indication relay being operative when energized to cause the auxiliary device to assume its second condition, and circuits controlled by said normal and reverse indication relays and adapted to control means for governing movement of trains over the track switch.
- 5 15. In combination, a railway track switch movable between a normal and a reverse position, means for moving said switch between said positions, an auxiliary device having a first condition and a second condition, a polarized relay, means operative when and only when the switch is in the normal position for supplying current of normal relative polarity to said polarized relay, means operative when and only when the switch is in the reverse position for supplying current of reverse relative polarity to said polarized relay, a normal and a reverse indication relay, means operable when the auxiliary device is in its first condition and the polarized relay is supplied with current of reverse polarity to establish a circuit 10 for energizing the reverse indication relay, means operative when the auxiliary device is in its second condition and the polarized relay is supplied with current of normal polarity for energizing the normal indication relay, the reverse indication relay being operative when energized and the polarized relay is supplied with current of reverse relative polarity to establish a stick circuit for energizing its own winding, the normal indication relay being operative when energized and the polarized relay is supplied with current of normal relative polarity to establish a stick circuit for energizing its own winding, the normal indication relay being operative when energized to cause the auxiliary device to assume its first condition, the reverse indication relay being operative when energized to cause the auxiliary device to assume its second condition, a control mechanism having a normal position in which it effects movement of the switch to the normal position and having a reverse position in which it effects movement of the switch to the reverse position, the control mechanism also controlling the circuits of the windings of the normal and reverse indication relays, said control mechanism being operable when and only when in its normal condition to establish the circuit of the normal indication relay and being operable when and only when in its reverse condition to establish the circuit of the reverse indication relay.
- 15 16. In combination, a railway track switch movable between a normal and a reverse position, means for moving said switch between its two positions, an auxiliary device having a first condition and a second condition, a normal and a reverse indication relay, a movable member movable between a normal and a reverse position in accordance with movement of the switch, means operative when the auxiliary device is in its first condition and the movable member is in the reverse position to energize the reverse indication relay, means operative when the auxiliary device is in its second condition and the movable member is in the normal position to energize the normal indication relay, the normal indication relay being operative when energized and the movable member is in the normal position to establish a stick circuit for energizing its own winding, the reverse indication relay being operative when energized and the movable member is in the reverse position to establish a stick circuit for energizing
- its own winding, the normal indication relay being operative when energized to cause the auxiliary device to assume its first condition and the reverse indication relay being operative when energized to cause the auxiliary device to assume the second condition, a polarized relay operative when and only when energized with current of normal relative polarity to effect movement of the switch to the normal position and to establish the circuit of the winding of the normal indication relay, said polarized relay being operative when and only when energized with current of reverse relative polarity to effect movement of the switch to the reverse position and to establish the circuit of the winding of the reverse indication relay, and a lock relay governed by traffic conditions in the vicinity of the switch, said lock relay being operative when energized to connect the winding of the polarized relay to a control circuit through which current of one or the other polarity may be selectively supplied to said relay winding, the lock relay being operative when released to connect the winding of the polarized relay to a supply circuit, the normal indication relay being operative when energized to establish a circuit through which current of normal polarity may be supplied to said supply circuit, the reverse indication relay being operative when energized to establish a circuit through which current of reverse polarity may be supplied to said supply circuit.
- 20 17. In combination, a railway track switch movable between a normal and a reverse position, a normal and a reverse indication device, an auxiliary relay having a contact movable between a first and a second position, said contact being operable in the first position to establish connection from a control circuit to a first supply circuit and being operable in the second position to establish connection from said control circuit to a second supply circuit, a source of current, a polarized relay, a member movable in accordance with movement of the switch and controlling a circuit for energizing the polarized relay, said member being operable in the normal position of the switch to supply current of normal relative polarity to the polarized relay and being operable in the reverse position of the switch to supply current of reverse relative polarity to the polarized relay, means controlled jointly by said member and a polar contact of said polarized relay for establishing connection from one terminal of said source of current to said control circuit, said means being operable to establish such connection when and only when said member and the polar contact of the polar relay are both in their normal positions or are both in their reverse positions, said polarized relay being also operable when its polar contacts are in their normal positions to establish connection from the second supply circuit to one terminal of the winding of the normal indication device and being operable when its polar contacts are in their reverse positions to establish connection from the first supply circuit to one terminal of the winding of the reverse indication device, means for establishing connection from the other terminal of the winding of either of the indication devices to the other terminal of the source of current, the normal indication device being operative when energized to energize the auxiliary relay to effect movement of its contact to its first position and to establish connection from said one terminal of said source to said second supply circuit, the reverse indication device being operative when energized to
- 25 30 35 40 45 50 55 60 65 70 75

energize the auxiliary relay to effect movement of its contact to its second position and to establish connection from said one terminal of said source to said first supply circuit.

- 5 18. In combination, a railway track switch movable between a normal and a reverse position, a normal and a reverse indication device, a source of current, an auxiliary relay having a contact constantly connected to one terminal of said
- 10 source of current, said contact being movable between a first position in which it establishes connection with a first supply circuit and a second position in which it establishes connection with a second supply circuit, a member movable
- 15 in accordance with movement of the switch, said member being operative when and only when the switch is in the normal position to establish connection from said second supply circuit to one terminal of the winding of the normal indication

device, said member being operative when and only when the switch is in the reverse position to establish connection from said first supply circuit to one terminal of the winding of the reverse indication device, means for establishing connection from the other terminal of the winding of either of the indication devices to the other terminal of the source of current, the normal indication device being operative when energized to establish connection from said one terminal of 10 said source to said second supply circuit and to energize the auxiliary relay to effect movement of its contact to its first position, the reverse indication device being operative when energized to establish connection from said one terminal of 15 said source to said first supply circuit and to energize the auxiliary relay to effect movement of its contact to its second position.

CHARLES W. BELL.
